US00D790366S

(12) **United States Design Patent** (10) Patent No.: **US D790,366 S**
(45) Date of Patent: ** *Jun. 27, 2017

(54) **ELECTRONIC DEVICE**

- (71) Applicant: **Samsung Electronics Co., Ltd.**, Suwon-si (KR)
- (72) Inventors: **Frank Nuovo**, Los Angeles, CA (US); **Sheldon George Phillips**, Glendale, CA (US); **Eduardo Salazar**, Reseda, CA (US)
- (73) Assignee: **SAMSUNG ELECTRONICS CO., LTD.**, Suwon-si (KR)
- (*) Notice: This patent is subject to a terminal disclaimer.
- (**) Term: **15 Years**
- (21) Appl. No.: **29/527,445**
- (22) Filed: **May 19, 2015**

Related U.S. Application Data

- (63) Continuation of application No. 29/491,654, filed on May 22, 2014, now Pat. No. Des. 729,652.

CLAIM

The ornamental design for an electronic device, as shown and described.

DESCRIPTION

FIG. 1 is a top left front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom left rear perspective view thereof.

The dashed broken lines are for environmental purposes only and form no part of the claimed design.

Any views of the electronic device that are not shown in the figures form no part of the claimed design.

1 Claim, 4 Drawing Sheets
